BRAIDER CARRIER

Frank Mossberg, Attleboro, Mass.

Application August 5, 1937, Serial No. 157,489

13 Claims. (Cl. 96—13)

This invention relates to a carrier for a braiding machine; and has for one of its objects the elimination of pawl and tooth arrangements for controlling the let-off of the package.

5 Another object of the invention is the provision of a means for nipping the yarn to control the let-off of the yarn from the package rather than the customary manner of controlling the support for the yarn.

10 Another object of the invention is the provision of a braider carrier which will accommodate a package of a larger size than packages usually accommodated.

15 Another object of the invention is the provision of a carrier which will have the stop for throwing off the stop lever of the braiding machine separate from the take-up means for the yarn.

20 Another object of the invention is the provision of a carrier with a single guide post with such resilient means as is utilized for the take-up housed within the guide post.

25 With these and other objects in view, the invention consists of certain novel features of construction, as will be more fully described, and particularly pointed out in the appended claims.

In the accompanying drawings:

Fig. 1 is a side elevation of a braider carrier showing the package in section;

30 Fig. 2 is a perspective view of the guide post with the operating parts mounted thereon;

Fig. 3 is a perspective view on a somewhat larger scale of the yarn nip and the yarn take-up which engages the same;

35 Fig. 4 is a perspective view of the yarn nip mechanism alone;

Fig. 5 is a sectional view through the lower portion of the guide standard showing the yarn take-up and its related parts;

40 Fig. 6 is a sectional view on line 6—6 of Fig. 5;

Fig. 7 is a top plan view of the guide arm mounted on the top of the post;

Fig. 8 is an elevation of a modified form of 45 carrier but with the same fundamental basic thought in view;

Fig. 9 is a central sectional view through the package spindle and package of the carrier of Fig. 8;

50 Fig. 10 is a perspective view of a modified form of nipping means for the yarn;

Fig. 11 is a detailed view showing the upper end of the guide standard with the yarn guide in section.

55 Fig. 12 is a sectional view through the base of

the carrier looking in the direction of the projection and showing the stop in lower position.

It is usual in braider carriers to provide a pawl on the carrier and a ratchet or toothed base on the package with which the pawl engages to control the let-off of the yarn on the package; and in order to eliminate this mechanism and simplify the control, I have provided a nip for the yarn which will be intermittently released by a usual take-up mechanism so that the package may be controlled through this nip means rather than through any control of a support for the package itself; and I have so arranged this carrier that the stop will be independent of the take-up means and located below the package that a larger package may be supported on the carrier than packages heretofore provided; and the following is a more detailed description of the present embodiment of this invention, illustrating the preferred means by which these advantageous results may be accomplished:

With reference to the drawings, 15 designates the base of the braider carrier provided with flanges 16 and 17 on either side of a web 18 which is guided through the race-way plate of 25 the braiding machine. Upwardly from this base there extends a boss 19 from which there extends a package spindle 20. A disk 21 with a depressed center portion 22 is supported on the shoulder 23 formed between the boss 19 and the 30 spindle 20 for the reception of the pasteboard cop 24 of the yarn package which extends below the package 25 of yarn when the same rests upon the upper surface of the disk 21. Suitable resilient bowed rods 26 are located along the spindle and spring outwardly when relieved from pressure, but when the cop is mounted on the spindle serve to friction the cop sufficiently so as to retard rotation of the package as the yarn 27 is drawn therefrom. A guide standard 30 is 35 supported in a recess 31 in the protuberance 32 of the base and has slidably mounted thereon a stop 33 having an opening 34 to receive the guide standard 30, there being an arm 35 bent over as at 36 and provided with an opening 37, 40 for also receiving this guide standard to direct the vertical movement of the stop along the standard. Fingers 38 on the stop extend inwardly and are positioned on either side of a stud 39 threaded into the base as at 40 and provided with a head 41 with which the fingers engage to limit the upward movement of the stop and prevent it from rising beyond the disk 21 which supports the package.

The yarn take-up is designated generally 42 55

and comprises a body portion 43 with a ring 44 at the lower end of the body extending at right angles to the body and encircling the guide standard 30 while at its upper end there is provided 5 an encircling ring 45 also extending about the guide standard 30. Between these two guides an arm 45 extends laterally from the body and is provided with a hook 47 beneath which the yarn passes, while there is a projection 48 extending upwardly beyond any of the other parts of the take-up for engaging and releasing the nipping mechanism which will be presently described.

The nipping mechanism comprises a collar 49 15 for encircling the guide standard 30 and bound in adjusted position thereon by means of the ears 50 and 51 with a bolt 52 extending through the ear 51 and into the threaded opening 53 in the ear 50. This collar has a bracket 54 extending therefrom with a bent-up finger 55 forming an eye 56 through which the yarn is guided. A resilient member 57 is secured by riveting or welding as at 58 to the bracket 54 and affords a resilient means to clamp the yarn between it 20 and the bracket as it is led therethrough. This resilient member 57 extends outwardly into the path of movement of the projection 48 on the take-up so that when this take-up engages the resilient member 57 it lifts the same to release 25 any yarn held between the bracket and this resilient member, this release being illustrated in Fig. 3.

Yarn from the package 25 is drawn upwardly 30 over the disk 75 having a stem 76 entering the pasteboard cop tube 24 and forming a guide for the yarn and thence through the opening 60 in the arm 61, and then extends downwardly through the opening 63 in this arm 61 to pass 35 through the eye 56 and beneath the resilient member 57, thence downwardly beneath the hook 47 and upwardly through the pigtail guide 65 supported at the upper end of the guide standard and thence to the braiding point. This guide 40 65 may be formed on the end of the pin 62 for pivoting supporting the arm 61 so that it may be rocked from working position to the position shown in dotted lines in Fig. 1 for removal and replacing of the package from the spindle 30. This hinging thus enables the guide to be located 45 closer to the bobbin.

A spring 66 housed within the tubular guide standard engages a hook 67 secured to the body of the yarn take-up at its upper end while its lower end engages a hook 68 secured to the arm 55 50 61 of the stop. The yarn thus lifts the take-up and through the spring the take-up lifts the stop, thus causing the stop to be lifted upwardly by reason of the spring, the take-up being drawn downwardly. As yarn is needed at the braiding point the yarn will cause the take-up to be lifted until its projection 48 engages the resilient member 57 to release the nip at this 55 point on the yarn, whereupon more yarn will be drawn through the nip mechanism from the package, the same turning if desired and the take-up member moving downwardly under action of its spring to take up any slack in the yarn, the yarn, however, acting to support the stop through the spring mechanism provided.

70 Should, however, the yarn break or fail by reason of exhaustion the take-up mechanism will then drop suddenly into engagement with the stop sliding it down the guide standard into a position which will throw off the lever of the braiding machine as the carrier moves into a

position to engage the part which it throws for this purpose. The protuberance 32 has slightly inclined sides 71 while the ends of the stop have a corresponding incline 78 to fit these sides 71 and thus support the stop in the shock 5 which it receives in actuating the stop lever of the braiding machine and relieving any strain which might otherwise occur on the pin 39.

In some instances instead of providing the nip mechanism closely adjacent the top of the 10 package I may provide a bracket arm 70, as shown in Fig. 10, extending from the collar 49 downwardly with the arm directed outwardly as at 71 and the guide mechanism 55 and resilient member 57 provided as heretofore. In this 15 case instead of drawing the yarn from the top of the package through a guide arm the spindle 20 is of a length to extend through the package and I provide an equalizing bail 72 over which the yarn is drawn from the package to this 20 guide eye 55 and thence beneath the hook 47 and then upwardly through the pigtail guide 73 at the upper end of the guide standard and thence to the braiding point. This pigtail guide is mounted in any suitable manner, such for 25 instance as on a screw 69 threaded into the end of the standard. The take-up mechanism and stop in this modified form of construction are the same as that previously described as are the other parts of the mechanism heretofore previously described.

The foregoing description is directed solely towards the construction illustrated, but I desire it to be understood that I reserve the privilege of resorting to all the mechanical changes 35 to which the device is susceptible, the invention being defined and limited only by the terms of the appended claims.

I claim:

1. In a carrier for a braiding machine, a package spindle, a rotatable package thereon, means to frictionally retard rotation of the package thereon, nip means including a pair of jaws one of which is inherently resilient to hold the yarn as it is led from the package, and means operable by the movement of the yarn to flex 45 said resilient jaw to release the yarn that it may be drawn therethrough and the package rotated.

2. In a carrier for a braiding machine, a guide standard, a package spindle, a rotatable package thereon, means to frictionally retard rotation of the package thereon, nip means including a pair of jaws mounted on the outer surface of said standard to hold the yarn as it is led from the package, means operable by the movement 55 of the yarn to release said nip means to permit the yarn to be drawn therethrough and the package to be rotated, and a guide carried by one of said jaws to direct the yarn from the package to between said jaws.

3. In a carrier for a braiding machine, a tubular guide standard, nip means mounted on attached to and out of axial alignment with said standard for holding the yarn as it is led from the package, and a yarn take-up member 65 60 slideable on said standard below said nip means and movable by the yarn into engagement with said means to release the hold on the yarn to permit yarn to be drawn therethrough, said member being urged in one direction by a spring located 70 within said tubular standard.

4. In a carrier for a braiding machine, a guide standard, a stop on said standard, nip means mounted on said standard for holding the yarn as it is led from the package, and a yarn take- 75

up member slidable on said standard below said nip means and above said stop and independent thereof and movable by the yarn into engagement with said means to release the hold on the 5 yarn to permit yarn to be drawn therethrough and means engageable with said yarn take-up for holding said stop in raised position.

5. In a carrier for a braiding machine, a guide standard, a stop on said standard, nip means mounted on said standard for holding the 10 yarn as it is led from the package, a yarn take-up member slidable on said standard below said nip means and above said stop, and a spring connecting said stop and member, said member being 15 movable by the yarn into engagement with said means to release the hold on the yarn to permit yarn to be drawn therethrough and also serving to hold said stop in raised position through said spring.

20. 6. In a carrier for a braiding machine, a guide standard, a stop on said standard, nip means mounted on said standard for holding the yarn as it is led from the package, a yarn take-up member slidable on said standard below said nip 25 means and above said stop, a spring connecting said stop and member, said member being movable by the yarn into engagement with said means to release the hold on the yarn to permit yarn to be drawn therethrough and also serving to 30 hold said stop in raised position through said spring, and means to limit the upward movement of said stop.

7. In a carrier for a braiding machine, a package spindle, a movable stop member, means for 35 limiting the upward movement of said stop at a point below the bottom of the package, take-up means for the yarn independent of but slidably mounted above said member and movable into engagement with said member to move the same to stopping position, and means comprising the 40 shape of said stop member and a part fixed to the base of the carrier to provide an interlocking connection between these parts and support the stop when it strikes the braiding machine stopping lever.

45. 8. In a carrier for a braiding machine, a stop member, take-up means for the yarn independent of but slidably mounted above said member and movable into engagement with said member to move the same to stopping position, said carrier having a base with a tapered projection and said stop member being provided with arms having edges to engage said projection and support the stop member when the same strikes the braiding machine stop mechanism.

50. 9. In a carrier for a braiding machine, nip means to hold the yarn as it is led from the pack-

age, said nip means including a pair of relatively movable jaw members secured together at one of their end portions, one of said jaw members having a portion extending a substantial distance beyond the edge of the other jaw member, and a 5 yarn take-up member movably mounted on said carrier and below said jaw members and provided with an extension thereon engageable with the extending portion of said jaw member to relatively move said jaw members to release the nip on the 10 yarn held therewith.

10. In a carrier for a braiding machine, a guide standard, a yarn take-up member slidably mounted on said guide standard and provided with an abutment thereon, nip means including a pair of 15 jaw members secured on the outer surface of said standard and between which the yarn is held as it is led from the package, said jaw members extending outwardly from said standard and provided with an extension thereon positioned in the 20 path of travel of said abutment to be moved thereby to relatively move said jaw members to release the nip on the yarn held therewith.

11. In a carrier for a braiding machine, a guide standard, a yarn take-up member slidably mounted on said guide standard and provided with an abutment thereon, a collar encircling said guide standard and provided with an arm extending therefrom, and a flexible member secured to said arm and overlying a portion thereof to hold the 30 yarn therebetween as it is led from the package, said flexible member having its free end positioned in the path of movement of said abutment to be moved out of engagement with the yarn.

12. In a carrier for a braiding machine, a standard, a package spindle, means to frictionally retard rotation of the package thereon, nip means including a clamping member adjustably secured to the outer surface of said standard and extending therefrom for holding the yarn as it is led 40 from the package, and means operable by the movement of the yarn to release said nip means to permit the yarn to be drawn therethrough.

13. In a carrier for a braiding machine, a package spindle, means to frictionally retard movement of the package thereon, a guide standard, nip means for holding the yarn as it is led from the package, means for securing said nip means on said standard including a collar substantially encircling said standard and adjustably secured thereto, and a yarn take-up member slidable on 45 said standard below said nip means and movable by the yarn into engagement with said means to release the hold on the yarn to permit yarn to be drawn therethrough.

FRANK MOSSBERG.
